(57) **CLAIM**

The ornamental design for a beverage container assembly, as shown and described.

DESCRIPTION

FIG. 1 is a front view of a beverage container assembly. FIG. 2 is a rear view of the beverage container assembly of FIG. 1.

FIG. 3 is a top view of the beverage container assembly of FIG. 1.

FIG. 4 is a bottom view of the beverage container assembly of FIG. 1.

FIG. 5 is a left-side view of the beverage container assembly of FIG. 1.

FIG. 6 is a right-side view of the beverage container assembly of FIG. 1.

FIG. 7 is an upper perspective view of the beverage container assembly of FIG. 1; and,

FIG. 8 is a lower perspective view of the beverage container assembly of FIG. 1.

The portions of the beverage container assembly shown in broken lines form no part of the claimed design.

1 Claim, 8 Drawing Sheets
